FLOW CONTROL HEAD

Arthur J. Penick and Kirby T. Penick, Houston,
Tex.

Application November 10, 1934, Serial No. 752,440

4 Claims. (Cl. 166—15)

This invention relates to a flow control head. An object of the invention is to provide a control head adapted to be attached to an outer pipe, or casing, in a well, to control the flow of 5 liquid, or gas, or both, from the well.

Another object of the invention is to provide an apparatus of the character described whereby the liquid and gas may be taken off separately from the well.

10 A further object of the invention is to provide apparatus of the character described whereby the fluid, either in the form of liquid or gas, flowing through the tubing and that flowing through the casing around the tubing may be taken off and delivered from the well through the same flow line or through separate flow lines.

A still further object of the invention is to provide an apparatus by means of which the fluid flowing under pressure from the casing may be 20 delivered into the tubing and forced downwardly therethrough to cleanse the tubing should the same become clogged up, and by means of which fluid flowing under pressure through the tubing may be delivered into the casing and forced 25 downwardly into the casing for unclogging the casing should the latter become clogged.

A still further object of the invention is to provide in apparatus of the character described a novel type of valve mechanism for controlling 30 the flow lines and having valves arranged to act either simultaneously or alternatively to control the corresponding line.

A still further object of the invention is to provide, in apparatus of this character a novel type 35 of tubing hanger equipped with novel means for securing the same in the head proper between the flow lines of the tubing and casing respectively.

The invention discloses certain improvements 40 over that type of tubing hanger and anchor support disclosed in our U. S. Patent No. 2,016,454 as well as certain movements over the controlling valve construction disclosed in our United States Patent No. 1,971,381.

45 With the above and other objects in view, the invention has particular relation to certain novel features of construction, operation, and arrangement of parts, an example of which is given in this specification and illustrated in the accompanying drawings, wherein:—

Figure 1 shows a side elevation of the flow control head, shown partly in section.

Figure 2 shows a vertical sectional view taken on the line 2—2 of Figure 1.

55 Figure 3 shows a fragmentary vertical sectional

view, showing a slightly modified form of tubing hanger.

Figure 4 shows a cross-sectional view taken on the line 4—4 of Figure 1.

Figure 5 shows a fragmentary sectional view 5 showing a novel type of valve mechanism for controlling the flow lines.

Figure 6 shows a fragmentary side elevation, partly in section, showing a slightly modified form of the apparatus shown in Figure 1, and 10

Figure 7 shows a side elevation of that type shown in Figure 6 taken at right angles to the view shown in Figure 6.

Referring now more particularly to the drawings wherein like numerals of reference designate 15 similar parts in each of the figures, the numeral 1 designates a tubular head adapted to be connected in any preferred manner to the upper end of the outer pipe, or casing 2, in the well. The head has an inside annular groove 3 forming 20 a seat. The lower side of this groove is preferably formed with an abrupt shoulder 4, and the upper side of the groove is preferably formed with an upwardly converging shoulder 5.

Secured in any preferred manner to the upper 25 end of the head, there is a valve casing 6 having the passageway 7 therethrough which may be opened or closed by the one-way, rotatable valve 8.

Secured, in any preferred manner, on the valve casing 6, there is a closure cap 9. When it 30 is desired to lower tools or other appliances through the head 1 into the well, for working

therein, the valve 8 may be opened and the cap 9 removed for that purpose; or, the cap 9 may be removed and flow connections attached instead 35 to the valve casing 6, if desired. There is a tubular hanger support 10 adapted to support the inner tubing 11, whose upper end may be

connected to the hanger support in any preferred manner, as by threads. This support 10 has 40 the external annular flange 12 thereon and surrounding, the support 10, and resting on the flange 12 there is an annular cage 13 having the external annular groove 14. This groove is of a

dove-tailed formation having the upper and 45 lower flanges 15, 16, one of which may be welded in place in process of construction. The supporting segments 17 are mounted in the groove 14, and are radially movable. Each segment has an upper flange 18, and a lower flange 19, en-

gageable against the corresponding flanges 15, 16, to retain the segments 17 in place. After segments 17 have been assembled in the groove 14, 50 one of the flanges 15 or 16 may then be formed by welding process. The segments 17 are seated 55

against the coil springs 20 which are interposed between said segments and the corresponding cage 13, and the segments are thereby held normally in their outer position.

5 In the form shown in Figure 2 there is a wedge ring 21 which surrounds the support 10 and which is mounted on the cage 13. This wedge ring has an upwardly and inwardly tapering face 22 on which the slips 23 are mounted. These slips have 10 the inner sides shaped to conform to the shape of and are seated on the tapering face 22 and have their outer sides provided with upwardly pitched teeth. On the slips 23 there is a ring 24 which closely surrounds the hanger support 10 and fits 15 closely within the head 1 and on this ring there are the packing rings 25 which in turn support the metal ring 26. The packing ring 25 closely surrounds the support 10 and fits closely within the head 1 and a jam nut 27 is threaded on to the 20 upper end of the support 10 and may be screwed down closely against the ring 26 to expand the packing to form a fluid-tight joint between the packing and support 10 and between the packing and the head 1 as well. A flange 28 may be 25 welded or otherwise secured to the upper end of the hanger support 10 to prevent the detachment of the jam nut beneath.

The upper end of the hanger support 10 may 30 be internally threaded, as at 29, for the connection of a section of pipe thereto, whereby the tubing 11 and the hanger therefor may be lowered into the head 1. While the tubing is thus being let into the well, the valve casing 6 should be removed from the head 1, and as the tubing 35 hanger is lowered when supporting segments 17 register with the groove 3, said segments will be forced outwardly by the springs 20 and segments will land on the shoulder 4 and thus support the tubing hanger and tubing.

40 In the form shown in Figure 3, the packing rings 25 are located directly on the ring 24 which in this instance is, in turn, supported on the cage 13. In this form shown in Figure 3 the wedge ring 21 is located directly on the packing 25 and 45 the slips 23' are located on the tapering face 22 of said wedge ring in the same manner as illustrated in Figure 2. These slips also have the external upwardly pitched teeth and also have the inside grooves 30. In this form the jam nut 50 27' threaded on to the upper end of the support 10, has an external annular flange 31 which fits in the groove 30.

When the tubing has been located in the well and is supported on the shoulder 4, the jam nut 55 27, or 27', as the case may be, may be screwed downwardly to expand the packer 25, as well as to force the slips 23, or 23', as the case may be, outwardly into engagement with the walls of the head 1 to anchor the tubing hanger and tubing so 60 that they will not be blown out by internal pressure in the well, and the valve casing 6 with the cap 9 thereon may then be installed in place.

When it is desired to remove the tubing from the well, the jam nut 27 or 27' as the case may be, 65 may be unscrewed, that is, may be screwed upwardly to release the packing. When the form of hanger shown in Figure 2 is used, and the packing is released, this will ordinarily relieve the pressure on the slips 23 sufficiently to permit the 70 tubing hanger and tubing to be withdrawn.

When the form of hanger shown in Figure 3 is used, as the jam nut 27' is screwed upwardly, the slips 23' will be moved upwardly and inwardly 75 sufficiently to cause the slips to release the tubing head 1 to permit the withdrawal of the tubing

hanger and tubing. It is to be noted that the segments 17 are provided at their upper ends with the upwardly tapering faces 32, and upon upward movement of the tubing hanger these tapering faces 32 engage the tapering shoulder 5 to cause 5 the retraction, or inward movement of the segments 17 to allow the hanger to move upwardly out of the tubing head 1.

As shown in Figures 1 and 2, the head 1 has the upper and lower valve housings 33, 34, preferably formed integrally therewith and of tubular formation and the head 1 has the upper and lower outlets 35, 36, above and beneath the hanger respectively. Splined in the housings 33, 34, are the valves 37, 38, whose forward ends are preferably beveled forming the annular faces 39, 40. The outer ends of the valve housings 33, 34, have the stuffing boxes 41, 42, respectively, secured therein, and the rotatable valve stems 43, 44, work through said stuffing boxes and have swiveling 20 connection therewith, but are confined against longitudinal movement. The inner ends of these stems are coarsely threaded through the nuts 45, 46, respectively of the valves 37, 38, whereby upon rotation of a valve stem, the associated valve will 25 be correspondingly moved into open or closed position as is obvious. A hand wheel 47 is provided for attachment to either of the stems to rotate the same.

A tubular manifold 48 is provided and has the 30 upper and lower annular flanges 49, 50, for connection to the mating flanges 51, 52, on the forward ends of the valve housings 33, 34 whereby the manifold 48 may be secured to said valve housings. This manifold has the upper and 35 lower outlet lines 53 and 54 controlled by suitable gate valves 55, 56.

The forward ends of the valve housings 33, 34 have the sleeve-like valve seats screwed therein through which the fluid flowing through the 40 outlets 35, 36 may enter the manifold 48. The valves 37, 38, may be either simultaneously or alternatively actuated into seated positions against the seats 51, 58, or into open positions. Between the valve seats 51, 58, the manifold 48 45 is formed into a valve casing 59 in which there is located a one-way rotatable valve 60 which is provided with a stem 61 whereby the valve 60 may be turned into open or closed position. In the form shown in Figures 4 and 5, a modified 50 form of valve mechanism for controlling the outflow of fluid into the manifold 48 has been disclosed. In connection with the disclosure of this form, it is to be understood that the outlet from the head 1 above the hanger, and the valve 55 mechanism for controlling said outlet, is identical with the outlet from the head beneath the hanger and the valve mechanism for controlling the same, as illustrated in Figure 5, only the lower outlet and valve mechanism being shown in said 60 Figure 5. In this form, the outlet 36' has a sleeve-like valve seat 58' screwed therein and a tubular valve housing 62 extends out at approximately right angles to the tubing head and is preferably formed integrally therewith. 65 Splined in the housing 62 there is a valve 63 and this valve has a threaded connection with the inner end of the stem 64 which is rotatable in, but confined against longitudinal movement relative to, the stuffing box 65 in the outer end of 70 the said valve housing 62, and by the rotation of said stem, the valve may be actuated in the position against the seat 58' to close the outlet or may be actuated into open position to permit the flow of fluid through said outlet, as indicated 75

in Figure 5. It is to be understood that in this form of construction shown in Figure 5, the head 1 is also provided with valve housings similar to the housings 33, 34, to which the manifold 48 (Figure 5) is connected. The lower housing referred to will be designated by the numeral 34a, and at its outlet end is provided with a sleeve-like valve seat 58a, similar to the seat 58, and which may be controlled by the valve 38 (see Figure 1). These control valves of Figure 5, to wit, the valves 38 and 63, are off-set relative to each other so that they may be simultaneously moved into a position to close the seats 58', 58a, or to simultaneously open them, or they may be alternatively actuated into either of said positions. This simultaneous or alternative action of the valve 38, 63, may be found desirable while making repairs or substitution of parts on the flow lines connected with them.

In the form shown in Figures 6, 7, there are the gate valve casings 66, 67, connected into respective out-flow openings 35, 36, and these casings may be opened and closed by the respective gate valves 68, 69. These valves are of conventional construction and may be opened and closed through the instrumentality of the hand wheels 70, 71. In this form of the structure the manifold 48 is attached to the respective valve housings 66, 67, as clearly shown in Figure 6.

In operation, the valve 60 may be opened and in the form shown in Figure 1 with the valves 37, 38, also open, the fluid from the well, be it either liquid or gas, may flow out into the manifold 48 and be led off through either, or both, of the flow lines 53, 54, depending on whether or not the valves 55, 56, are opened or closed, and a like result may be obtained when the form in Figure 5 is used, by opening both valves controlling the upper and lower outlets from the tubing head, and if the form shown in Figure 6 is employed, a like result can be obtained by opening the valves 68 and 69. By closing the valve 60, the out-flow from the casing may be led off through the line 54, or, the outlet from the casing may be closed by closing the valve 56 or the valve 38; and, with the valve 60 closed, the out-flow of the well from the tubing may be led off through the line 53, or may be closed off by closing the valve 55, or the valve 37. In the form shown in Figure 6, it is obvious that by suitably manipulating the valves 68, 69, the outlet from the tubing and the casing may be controlled at will, and the outlet from either or both may be let off through the outlet line 53, 54, or both of them by suitably manipulating the valve 60.

It sometimes happens that the tubing 11 may become clogged up; in such case the valves 55, 56, may be closed, and the valve 60 opened. The upper valve 37 or 68 and the lower valve 38 or 69 may also be opened, and the fluid under pressure may then flow from the casing and be forced down into the tubing to force out the clogging material and cleanse the tubing; or, on the other hand, the casing may become clogged up, in which case, with the valves set, as last above described, the fluid under pressure will flow up through the tubing and back down through the casing so as to force out the clogging material, relieving the congestion in the casing.

The drawings and description disclose what are now considered to be preferred forms of the invention by way of illustration only, while the

broad principle of the invention will be defined by the appended claims.

What we claim is:

1. In a flow controlling apparatus, a tubular head adapted to be attached to a pipe in a well, a tubular branch formed integrally with and extended laterally from the head and having an inside removable seat adjacent the head, a valve movable axially in said branch into one position to close the seat and into another position to open the seat, means for actuating the valve into either of said positions, a flow tube leading out from said branch, out beyond said seat, and being offset vertically with respect to said seat, a valve seat within and adjacent the inner end 15 of said tube, a valve movable axially with respect to said flow tube and arranged to control said last mentioned seat, means for actuating the last mentioned valve into open or closed position, said valves being independently movable and being arranged to simultaneously or alternatively open and close said seats.

2. A flow controlling apparatus comprising a tubular head having outlets at different elevations, a tubing hanger in the head adapted to support a tubing, means for supporting the hanger between the outlets, upper and lower valve housings of tubular formation on the head whose forward ends are formed with flanges, a valve in each housing movable axially with respect thereto for controlling the corresponding outlet, a tubular manifold connecting said outlets and having upper and lower flanges arranged to register with the corresponding housing flanges, means for securing said flanges together. 30

3. A flow controlling apparatus comprising a tubular head having outlets at different elevations, a tubing hanger in the head adapted to support a tubing, means for supporting the hanger between the outlets, upper and lower valve 40 housings of tubular formation on the head whose forward ends are formed with flanges, a cylindrical valve in each housing and movable axially therein for controlling the corresponding outlet, a tubular manifold connecting said outlets and 45 having upper and lower flanges arranged to register with the corresponding housing flanges, means for securing said flanges together, a valve casing incorporated into said manifold and a valve in said casing for controlling the flow of 50 fluid through the manifold.

4. A flow controlling apparatus comprising a tubular head adapted to be attached to a pipe in a well and having a conduit leading outwardly therefrom, an inner removable valve seat at the inner end of said conduit, a valve housing extended outwardly from the head in alignment with said seat, a valve in said housing movable into one position into cooperation with said seat to close the conduit and into another position to open the conduit, an outer valve seat around the conduit and offset with respect to the inner valve seat, a valve housing in alignment with said outer valve seat, a valve in said last mentioned housing movable into and out of cooperating relation with the outer valve seat to control said conduit, said valves being offset relative to each other so that they may be simultaneously, or alternatively opened and closed and a valve beyond the outer valve seat for opening and closing the conduit. 70
